UNITED STATES PATENT OFFICE.

LIONEL NORMAN AND EDWARD C. BATES, OF BOSTON, MASSACHUSETTS, ASSIGNEES,
BY MESNE ASSIGNMENTS, TO PURE FOOD PACKAGE COMPANY, OF BOSTON, MASSA-
CHUSETTS, A CORPORATION OF MASSACHUSETTS.

MACHINE FOR APPLYING END CLOSURES TO PAPER VESSELS.

1,053,314.

Specification of Letters Patent. Patented Feb. 18, 1913.

Application filed May 9, 1910. Serial No. 560,370.

To all whom it may concern:

Be it known that we, LIONEL NORMAN and EDWARD CARRINGTON BATES, citizens of the United States, residing at Boston, in the county of Suffolk and State of Massachusetts, have invented certain new and useful Improvements in Machines for Applying End Closures to Paper Vessels; and we do hereby declare the following to be a full, 10 clear, and exact description of the invention, such as will enable others skilled in the art to which it appertains to make and use the same.

The principal object of the present invention is to provide a machine by which an end closing cap may be forced into the interior of the vessel for a short distance and by which the projecting edge of the closing cap may be folded over upon the outside of 20 the vessel.

Another object of the invention is to provide improved means for folding over the projecting edge of an end closing cap upon the outside of a vessel.

With the above objects in view the present invention contemplates the provision in a machine for applying end closures of a suitable support for the vessel, a cap-punch arranged to force an end closing cap into 30 the interior of the vessel and a sealing punch arranged to fold over the projecting edge of the cap upon the outside of the vessel. Broadly considered, the two punches may be constructed and arranged in any 35 suitable manner. To provide a simple and compact construction, however, and to permit the entire operation of closing the end of the vessel to be performed quickly without excessive relative movement of the two punches 40 and vessel, the sealing punch is preferably mounted concentric with the capping punch. This construction has the further advantage that the punches can be so arranged that the sealing punch operates while the capping 45 punch is projecting into the vessel so that the two punches coöperate to press the closing cap snugly against both the inner and outer surfaces of the vessel. With this construction also the center portion of the cap 50 is held in position during the operation of the sealing punch.

In accordance with another feature of the present invention a rotary, as well as a longitudinal movement, is imparted to the

sealing punch. By imparting a rotary 55 movement to the sealing punch the cap is more effectively applied to the outside of the vessel and all wrinkles which may be formed in the cap are smoothed down. Broadly considered, this feature of the invention is 60 not limited to a construction in which a capping punch is used which forces the cap into the interior of the vessel.

The present invention will be clearly understood from an inspection of the accompanying drawings in which—

Figure 1 is a view in side elevation of a machine embodying the same in the preferred form. Fig. 2 is a view in front elevation of the machine illustrated in Fig. 1. 70 Fig. 3 is a fragmentary sectional view of the capping and sealing punches and the holder for the vessel, a vessel being shown in the holder with a closing cap placed thereon in position to be operated upon by the punches. 75 Fig. 4 is a view similar to Fig. 3 showing the position of the parts after the closing cap has been forced into the interior of the vessel by the capping punch and Fig. 5 is a similar view illustrating the position of the parts 80 after the sealing punch is operated.

The capping punch of the machine is indicated at 1 and is provided with a cylindrical lower end of a size to fit snugly within the end of the vessel to which the end closure is 85 to be applied.

The sealing punch is indicated at 2 and consists of a sleeve mounted upon the punch 1 and provided at its lower end with a recess 3 to fit snugly on the outside of the vessel. The sealing punch is mounted upon the capping punch so as to move therewith toward and from the vessel and so as to be capable of an independent longitudinal and rotary movement. To this end the capping 95 punch 1 is provided with a number of radially extending pins 4 which pass through slots 5 so shaped that a longitudinal movement is imparted to the sealing punch when it is rotated on the capping punch. To enable the sealing punch to be operated conveniently it is provided with a laterally projecting handle 6.

The capping punch 1 is secured to the cross-head 7 mounted to reciprocate in the 105 overhanging head of the machine and connected to an actuating treadle 8 by a pivoted lever 9 and link 10.

Below the punch 1 and in alinement therewith, a holder 11 is provided for the vessel to which the end closure is to be applied. This holder consists of a block provided with a suitably shaped opening to receive and support the vessel, the block being mounted upon the base of the machine. To enable the end closing cap to be readily placed in correct position to be acted upon by the cap and sealing punches, a semicircular gage 12 is provided secured to the rear side of the holder 11.

The operation of the capping and sealing punches will be clearly understood from an inspection of Figs. 3, 4 and 5. The end closing cap 13 is first placed in position, as indicated in Fig. 3. This cap preferably consists of a central disk of card-board of the desired thickness which fits inside of the vessel and a thin sheet of flexible material, the edge of which projects beyond the wall of the vessel. The under surface of this flexible material is preferably provided with adhesive. The cap 13 being in position on the vessel, the treadle 8 is operated to depress the capping and sealing punches to the position illustrated in Fig. 4. The capping punch forces the cap into the interior of the vessel for a short distance, the projecting edge of the cap drawing underneath the lower edge of the sealing punch and being held in a substantially horizontal position thereby. The sealing punch is now rotated by means of the handle 6 and is caused to fold over the projecting edge of the cap upon the outside of the vessel as indicated in Fig. 5, the rotary movement of the punch smoothing out the wrinkles. When the sealing punch is in its lowest position, as indicated in Fig. 5, the layers of the cap 13 are pressed tightly against the inner and outer walls of the vessel so that a tight closure of the vessel, or sealing of the vessel, is secured.

The nature and scope of the present invention having been indicated and a machine embodying the several features of the invention in their preferred form having been specifically described, what is claimed is:—

- 50 1. A machine for applying end closures to paper vessels, having, in combination, a support for the vessel, a capping punch to force a closing cap into the interior of the vessel, a sealing punch, and means for actuating the sealing punch after the cap has been forced into the vessel to engage the edge of the cap projecting outwardly over the edge of the vessel and fold said projecting edge downwardly upon the outside of the vessel.
- 60 2. A machine for applying end closures to paper vessels, having, in combination, a support for the vessel, a capping punch to force a closing cap into the interior of the vessel, a sealing punch mounted concentric with the capping punch, and means for moving the

sealing punch longitudinally after the cap has been forced into the vessel to engage the edge of the cap projecting outwardly over the edge of the vessel and fold said projecting edge downwardly upon the outside of the vessel. 70

3. A machine for applying end closures to paper vessels, having, in combination, a support for the vessel, a capping punch to force a closing cap into the interior of the vessel 75 and a sealing punch longitudinally movable and rotatably constructed to engage the edge of the cap projecting outwardly over the end of the vessel and fold said projecting edge downwardly upon the outside of the vessel. 80

4. A machine for applying end closures to paper vessels, having, in combination, a support for the vessel, a capping punch to force a closing cap into the interior of the vessel, 85 a sealing punch mounted concentric with the capping punch and movable longitudinally with relation to the capping punch and rotatably constructed to engage the edge of the cap projecting outwardly over the end 90 of the vessel and fold said projecting edge downwardly upon the outside of the vessel.

5. A machine for applying end closures to paper vessels, having, in combination, a support for the vessel, a capping punch to force 95 a closing cap into the interior of the vessel, a sealing punch mounted concentric with the capping punch to fold over the projecting edge of the cap upon the outside of the vessel, and pin and slot connections between 100 the two punches to permit a longitudinal and rotary movement of the sealing punch with relation to the capping punch.

6. A machine for applying end closures to paper vessels, having, in combination, a support for the vessel, a capping punch to force a closing cap into the interior of the vessel, and a sealing punch mounted to move with the capping punch while the cap is being forced into the vessel and having a further 110 independent longitudinal movement and being constructed to engage the edge of the cap projecting outwardly over the end of the vessel and fold said projecting edge 115 downwardly upon the outside of the vessel.

7. A machine for applying end closures to paper vessels, having in combination, a support for the vessel, a sealing punch, constructed to engage the edge of a cap projecting outwardly over the end of the vessel and fold said projecting edge downwardly upon the outside of the vessel, and means for holding the central portion of the cap in position during the operation of the sealing punch. 120

8. A machine for applying end closures to paper vessels, having, in combination, a support for the vessel, a longitudinally movable and rotatable sealing punch constructed to engage the edge of a cap projecting out- 130

wardly over the end of the vessel and fold said projecting edge downwardly upon the outside of the vessel and means for holding the central portion of the cap in position during the operation of the sealing punch.

9. A machine for applying end closures to paper vessels, having, in combination, a support for the vessel, a reciprocating capping punch to force a closing cap into the interior of the vessel, a sealing punch mounted on the capping punch so as to move therewith, a handle for operating the sealing punch independently of the capping punch and connections between the two punches to impart a longitudinal and rotary movement to the capping punch when operated to fold

over the projecting edge of the cap upon the outside of the vessel.

10. A machine for applying end closures to paper vessels, having, in combination, a holder for the vessel, a capping punch mounted in alignment with the holder and movable to force a closing cap into the interior of the vessel, a gage to position the cap and a sealing punch mounted concentric with the capping punch and movable to fold over the projecting edge of the cap upon the outside of the vessel.
